UNITED STATES PATENT OFFICE.

JOSEPH SZTARÝ AND LOUIS KOVÁCS, OF BELLAIRE, OHIO.

DIRECTION-SIGNAL.

1,347,420.

Specification of Letters Patent. Patented July 20, 1920.

Application filed February 28, 1920. Serial No. 362,073.

To all whom it may concern:

Be it known that we, JOSEPH SZTARÝ and LOUIS KOVÁCS, citizens of Hungary, residing at Bellaire, in the county of Belmont and 5 State of Ohio, have invented new and useful Improvements in Direction-Signals, of which the following is a specification.

This invention relates to direction signals for motor vehicles or the like and comprehends a construction wherein the various parts are compactly arranged so as to produce a comparatively small device which can be readily and easily mounted upon a convenient part of the machine.

10 To this end, the invention employs a pair of sliding indicating members, normally disposed within a casing and adapted to be singly extended for use through the instrumentality of a flexible element, which can be quickly and easily attached to an appropriate part of the machine to hold the indicator in its extended position against the tension of resilient means which function to hold the indicator in its normal position.

15 The nature and advantages of the invention will be better understood when the following detail description is taken in connection with the accompanying drawings, 20 the invention residing in the construction, combination and arrangement of parts as claimed.

In the drawings forming part of this specification, like numerals of reference indicate similar parts in the several views and 25 wherein:—

Figure 1 is a front elevation partly in section of the signal device forming the subject matter of the invention.

40 Fig. 2 is a transverse sectional view taken through Fig. 1.

Fig. 3 is a horizontal sectional view taken through Fig. 1.

Fig. 4 is a detail view of one of the hooks 45 for holding the indicator in extended position.

Fig. 5 is a detail view showing the terminal of one of the flexible elements associated with the hook.

50 Referring to the drawing in detail, 10 indicates a casing which may be constructed from any suitable material, and desired size, the casing by preference being of rectangular formation in cross section. Arranged 55 within the casing 10 is a pair of slides 11 and 12 respectively, both being of substan-

tially the same area and arranged one behind the other. Upon one side of each slide, a hand 13 is painted or otherwise provided, so that when one of the slides is projected from the casing in a position for use, it will indicate to pedestrians and to drivers of other machines, the particular direction to be pursued. Projecting from the front and rear walls 14 and 15 respectively of the 60 casing, are channel shaped members 16 for each slide, these channels supporting each slide and guiding it in its movements as will be readily understood. Arranged beneath the top wall 18 of the casing is a pair 65 of horizontally disposed springs 19 and 20, respectively, the adjacent terminals of said springs being secured to the top of the casing in any suitable manner as shown. The spring 19 has its opposite end secured to the 70 adjacent end of the slide 11 through the instrumentality of the flexible member 21 while the corresponding end of the spring 20 is secured to the adjacent end of the slide 12 through the instrumentality of the member 22 similar to that indicated at 21. A tubular element 23 incloses the springs 19 and 21 to protect the latter from the effects 75 of dirt and other foreign matter. The springs function to normally maintain the 80 slides 11 and 12 positioned within the casing 10, one behind the other as shown in Fig. 1. The slides are adapted however to be snugly projected through the opposite ends of the 85 casing 10 for the purpose hereinabove stated. 90

A flexible element 25 is provided for each slide, and the corresponding extremities of these elements 25 are secured in any suitable manner to the lower extremities of the slides 11 and 12. Arms 26, preferably project from the slide to provide a connection between the latter and the flexible elements 25. The elements 25 extend in opposite directions from their point of connection with the slide and are trained over pulleys 27 95 journaled at the lowermost corners of the frame, the flexible elements extending to a position within convenient reach of the operator. When it is desired to project one or the other of the slides to an active position, 100 the proper element 25 is pulled upon, thereby moving said slide to its projected position against the tension of the spring with which it is associated. When the particular element 25 is released, the spring functions to automatically retract the slide to its 105 normal position. For the purpose of hold-

ing the slide in an extended position, we provide each of the operating elements 25 with a knob 28 which is adapted to be received by a hook 29 of any suitable character secured to an appropriate part of the machine. Of course the hook 29 will be so positioned that when the flexible element is pulled upon to project the slide, the knob may be positioned within the hook 29 to 10 hold the flexible element taut and the slide projected. The component parts of the device are compactly and neatly arranged, so as to minimize, the size, thus permitting the same to be applied to the machine without 15 occupying any appreciable amount of space.

While we have shown and described what we consider the preferred embodiment of the invention, we desire to have it understood that we do not limit ourselves in this connection, and that such changes may be resorted to when desired as fall within the scope of what is claimed.

Having thus described our invention what we claim as new is:—

- 25 1. A direction signal comprising an elongated casing having a slot at each end, said slots being staggered, a pair of slides arranged one behind the other within the casing, means for normally holding the slides 30 positioned within the casing, upper and lower channel shaped guide members for each slide, the lowermost member of each pair having a longitudinal slot, a pin pro-

jecting from the lower edge of each slide and through said slot, flexible elements having their adjacent ends secured to said pins, the bottom of the casing having spaced openings through which the flexible elements are threaded, whereby said slides may be singly projected beyond the ends of the 40 casing, each slide having a hand or indicator thereon.

2. A direction signal, an elongated casing having a slot at each end, a pair of slides arranged one behind the other within the 45 casing, upper and lower channel shaped guides for each slide, the lowermost guide of each pair having a longitudinal slot, a pin projecting from the adjacent edge of each slide and through said slot, flexible elements having their adjacent ends secured to said pin, the bottom of the casing having spaced openings through which said flexible elements are threaded, a hollow tubular member arranged above each of the upper- 50 most guide members, a coiled spring housed within said tubular member and having one end secured to the adjacent end wall of the casing, and a flexible connection between the opposite end of the spring and the adjacent end of the slide as and for the purpose specified.

In testimony whereof we affix our signatures.

JOSEPH SZTARY.
LOUIS KOVÁCS.
